PROCESSES AND APPARATUS FOR RECOVERING HYDROCARBONS FROM GAS STREAMS

Willard M. Dow, Houston, Tex., assignor to Delta Tank Manufacturing Company, Baton Rouge, La., a corporation of Louisiana

Filed Dec. 20, 1957, Ser. No. 704,078

8 Claims. (Cl. 208—340)

This invention relates to new and useful improvements in processes and apparatus for recovering hydrocarbons from gas streams.

There are in general commercial use various processes for hydrocarbon recovery, including gasoline recovery, from natural gas streams and one such process is disclosed in my co-pending application Serial No. 667,440, filed June 24, 1957, now Patent No. 2,880,818. In these processes the objective is to extract the hydrocarbons, including the lighter fractions such as propane, butane and gasoline, from the gas stream and it has been the practice to conduct the recovered hydrocarbons directly to the stock tank. However, since the recovered hydrocarbons include the so-called lighter fractions, the recovered hydrocarbon liquids are somewhat unstable and actually, when such liquids are conducted directly from the hydrocarbon recovery process or unit and flashed into the stock tanks, a considerable loss of valuable lighter constituents occurs.

Many well streams, which are to be subjected to processing through a hydrocarbon recovery apparatus are two phase streams, that is the stream includes a liquid phase and a gas phase. Ordinarily in such case the liquid phase is composed of the heavier hydrocarbon liquid components while the gas phase includes the lighter hydrocarbon components such as the propane, butane and gasoline fractions which it is desired to recover as a liquid by means of the hydrocarbon recovery adsorption or other process. Where a two phase well stream is to be treated, the overall or final recovery of the desirable hydrocarbon components may be increased by combining certain other steps with the usual hydrocarbon recovery process or apparatus which is normally employed for extracting hydrocarbons from a gas stream.

It is therefore one object of this invention to provide an improved process for treating a two phase main stream which increases the efficiency of final recovery of the desirable hydrocarbons from the stream, whereby increased recovery of such hydrocarbons is effected.

An important object is to provide an improved process for treating a two phase hydrocarbon stream which includes initially separating the gas from the heavier hydrocarbon liquids in said stream, extracting additional hydrocarbons from the gas and then contacting the hydrocarbons so recovered in the extraction step with the liquids which were initially separated from the main stream, whereby the hydrocarbons recovered through the extraction step are retained and a stable liquid product is produced.

A further object is to provide an improved process for increasing the recovery of hydrocarbons from a two phase main stream wherein the normal heavier liquids are initially separated from the gas in said stream and are conducted to a stabilizer unit and also wherein the separated gas is subsequently treated to recover lighter hydrocarbon liquids therefrom, after which the lighter hydrocarbon liquids so recovered are directed in counter-current flow to the heavier liquids initially separated from

2

the main stream and are contacted therewith, whereby the resultant liquid product is stabilized and may be directed to storage.

Still another object is to provide an improved process, of the character described, wherein any conventional type of separator may be employed to effect the separation of gas and liquid from the main stream and also wherein the separated gas may be subjected to any suitable treating process for extracting the desirable hydrocarbon liquids from said gas; the process also permitting the use of any suitable type of stabilizer which will effect an intimate contact of the hydrocarbon liquids recovered from the gas treating step and the heavier liquids which were initially separated from the main stream.

A particular object is to provide an improved process which lends itself to use with the process disclosed in my co-pending patent application Serial No. 667,440, now matured into Patent No. 2,880,818 such prior process being combined with additional steps which accomplish an overall increase in the recovery of desirable hydrocarbon constituents and produce a stable liquid product.

The construction designed to carry out the invention will be hereinafter described, together with other features thereof.

The invention will be more readily understood from a reading of the following specification and by reference to the accompanying drawing forming a part thereof, wherein an example of the invention is shown, and wherein:

Figure 1 is a flow diagram of the apparatus for carrying out the process of this invention.

In the drawing the numeral 10 designates an inlet conductor which may extend from a well or from some other suitable source and which is adapted to conduct a two phase main stream to a conventional liquid and gas separator 11. As is well known, a two phase stream is one which contains some constituents or components in the gas phase and other constituents or components in the liquid phase. The gas phase of the stream includes desirable hydrocarbons generally referred to as the lighter ends or fractions and these may include the butanes, propanes and gasoline fractions. The liquid phase ordinarily consists of the so-called heavier ends or fractions which are stable liquids under the particular pressure and temperature conditions.

The two phase main stream is conducted to the separator 11 and within said separator a separation of the gas from the heavier liquids is accomplished. The separated gas escapes from the upper portion of the separator 11 through a gas line 12 while the separated liquids flow from the lower portion of said separator through the outlet line 13. A suitable valve 14 is connected in the line 13 and is controlled in the usual well known manner by a float 15 disposed within the interior of the separator. The outlet line 13 extends to the upper portion of a combination separator-stabilizer vessel A which will be hereinafter described in detail.

Since the gas, which has been separated in separator 11, contains desirable hydrocarbons, which can be extracted or removed therefrom as liquid, the gas is conducted through line 12 to a hydrocarbon recovery unit, which is generally indicated by the letter B, such unit being enclosed within the dotted line of Figure 1. Although various types of hydrocarbon recovery units or processes may be employed to extract and recover hydrocarbons from gas streams, it is preferable to employ the particular adsorption apparatus and process which is disclosed in detail in my Patent No. 2,880,818. This particular type of apparatus and process includes a pair of adsorbing towers or vessels 16 and 17 and each tower has a bed of suitable adsorbing material, such as silica gel or activated charcoal, disposed therein. The gas line

12 extending from the separator vessel 11 has connection with a three-way control valve 18 and said valve is, in turn, connected with the upper ends of the towers by lines 16a and 17a. Depending upon the position of the three-way valve, gas flow is to either one or the other of the towers 16 and 17.

Assuming that the gas flow is through tower 16, said gas contacts the adsorption material therein and such material has an adsorbing efficiency for the lighter hydrocarbons such as propane, butane and gasoline fractions. The gas is conducted from tower 16 through outlet line 16b, three-way valve 19 and outlet conductor 20. The outlet conductor connects with a heat exchanger 21 and after passing through the heat exchanger, the gas is directed to sales or other disposition through the discharge line 22.

While tower 16 is on an adsorbing cycle, a regenerating gas flows from a heater 23 through line 24, past three-way valve 25 and into the tower 17 with this latter tower being on a regenerating cycle. The regenerating gas is, of course, heated and functions to regenerate or reactivate the bed within the tower 17 by stripping or removing the hydrocarbons which were adsorbed by the bed during the preceding cycle. The heated regeneration gas picks up such hydrocarbons and carries them as vaporized liquids from tower 17 through a line 26, past a three-way valve 27 and through conductor 28 to an atmospheric type heat exchanger 29. Heat exchanger 29 functions to begin cooling of the regenerating gas stream and said stream is then conducted through the line 30 to the heat exchanger 21 where it is passed in heat exchange relationship to the discharging main gas stream flowing through conductor 20 and discharge line 22. Further cooling of the regeneration gas is accomplished in the heat exchanger 21 and said regeneration gas stream then passes through conductor 31 to a liquid accumulator 32. The cooling of the gas by the heat exchangers 29 and 21 results in condensing the hydrocarbon fractions which have been picked up by the gas and these condensed liquid fractions drop out of the regeneration gas stream as it flows through the liquid accumulator 32. The regeneration stream from which the liquids have been removed is then recirculated through line 33, pump 34 and line 35, back to the heater 23. The liquids are withdrawn from the accumulator vessel 32 through a discharge line 36.

In the operation of the hydrocarbon recovery apparatus and process B, the towers 16 and 17 are alternately on an adsorbing and a regenerating cycle, this being accomplished by automatically actuating the various three-way valves 18, 19, 25 and 27 to switch the flows. Thus, a substantially continuous process is obtained.

As has been noted, the liquids, which were initially separated from the main stream in the separator 11, are conducted from the lower portion of the separator through discharge line 13 and into the upper portion of the separator-stabilizer vessel A. These liquids comprise the heavier hydrocarbons and are stable as liquids at the particular operating pressures and temperatures. It is desirable that the vessel A be operated at a lower pressure than the separator 11 whereby a flashing of the lighter constituents contained in the liquids conducted from the separator 11 will occur as said liquids are introduced into the upper portion of the vessel A. This flashing of the lighter constituents will further stabilize the liquids which, as will be explained, subsequently pass downwardly within the vessel A. It is pointed out that if necessary, desired stabilization of the liquids separated in the separator 11 may be accomplished in any well known manner as, for example, by the application of heat which may be carried out by mounting a heat exchanger in the discharge line 13. By heating, the liquid lighter constituents would be driven off and would be separated from the liquid within the upper portion of the vessel A.

The separator-stabilizer vessel A is shown schematically and includes a separating chamber 37 in its upper portion

with a stabilizer section 38 therebelow. The lighter constituents contained in the liquid entering the vessel through line 13 are separated in the separator section and escape from the upper end thereof through the conductor 37a, while the liquid flows downwardly through the stabilizer section 38. Said stabilizer section may be of any desired or conventional construction and, as illustrated, includes a plurality of inclined contact trays; said section may, if desired, employ the well known bubble tray arrangement or may be a packed section which functions to produce intimate liquid-gas contact.

The discharge line 36 extending from the liquid accumulator 32 of the adsorption apparatus B is connected into the lower portion of the separator-stabilizer A and a suitable float-controlled valve 40 is disposed in this line, said valve being actuated by a float 41 located within the accumulator vessel 32 of the adsorption apparatus B. Thus, the hydrocarbons extracted by the apparatus and process B are conducted to the lower portion of the vessel A, which is operated at a lower pressure than the apparatus B, so that said extracted liquids are flashed into the lower end of said vessel. The flash vapors will obviously rise upwardly through the stabilizer section 38.

25 The heavier hydrocarbon liquids, which are substantially stable at the operating pressures and temperatures having been introduced into the upper end of the vessel A, flow downwardly through the stabilizer section 38 and are thus directed in countercurrent flow to the vapors 30 rising within said section. This results in the downwardly flowing heavier hydrocarbon liquids intimately contacting the upwardly flowing flash vapors and lighter fractions as the same pass through the stabilizer section 35 whereby the heavier, more stable liquids pick up the lighter vapors and fractions with the mixture passing downwardly to the bottom of the vessel A. Any of the 40 extracted liquid, which has not vaporized upon entry into the vessel A will, of course, flow downwardly to the bottom and the final liquid product is discharged from vessel A through an outlet line 42. Any flash vapors, which are not picked up by the countercurrent flow of the heavier, less volatile liquid, are discharged from the upper end of vessel A through the line 37a.

45 The liquid product escaping from the separator-stabilizer is a mixture of the initially separated heavier hydrocarbon liquids and the extracted lighter hydrocarbon liquids and provides a final product which is a stable liquid. This stable liquid is conducted from the vessel A through the discharge conductor 42 which has 50 its opposite end connected to the usual stock tank 44. Flow through the discharge conductor 42 is controlled by a valve 43 which is actuated by a float 45 mounted within the separator section of the separator-stabilizer vessel A.

55 From the foregoing it will be seen that the process contemplates the treating of a two-phase stream, which may be a well stream, to recover increased quantities of desirable hydrocarbon constituents. The main stream is first directed to the conventional separator wherein the gas phase is separated from the liquid phase. The 60 separated gas phase of the stream is then conducted through a suitable hydrocarbon recovery apparatus and process, such as the adsorption apparatus and process B, wherein the lighter, more volatile hydrocarbon constituents are recovered. Thereafter, the initially separated liquid phase, which constitutes a liquid which is heavier, more stable and less volatile, is directed in countercurrent flow to the vapors of the more volatile, lighter liquids, which have been extracted by the adsorption process B.

65 The separator-stabilizer vessel A is operated at a lower pressure than is the adsorption unit A so that a flashing of the extracted, more volatile liquids will occur and the flashed vapors, moving in countercurrent flow to the heavier liquids, are picked up by said liquids and become a part thereof. The liquid removed from the

lower end of the stabilizer A is in a stabilized condition and may be conducted to the liquid stock tank 44 in the usual manner. Having been stabilized, the loss from vaporization in the stock tank is minimized and the final result is an increased recovery of the desirable hydrocarbon constituents.

Actual practice has shown that recoveries have been substantially doubled by the use of the process herein disclosed. As an example, where the accumulated liquids are conducted from the accumulator vessel 32 of the adsorption apparatus B directly to the stock tanks, a given gas stream provided a hydrocarbon liquid recovery of 13.2 barrels per day. Where this same gas stream was treated and its hydrocarbon liquid recovery was conducted to the separator-stabilizer vessel A and contacted with 100 barrels per day of the heavier liquids flowing from separator 11, the recovery of the hydrocarbon liquids from the gas stream was increased to 27.8 barrels per day. The difference in this recovery is accomplished by contacting the lighter, more volatile hydrocarbons, which are extracted from the gas in the adsorption apparatus B, with the heavier previously separated, less volatile liquids in the separator-stabilizer vessel. The heavier liquids contacting the lighter liquids in countercurrent flow pick up the more volatile fractions which would otherwise escape to atmosphere and the liquid flowing from the stabilizer vessel A is in a stabilized condition providing a stable liquid product which will remain in the stock tank.

As has been noted, any suitable adsorption process or apparatus may be employed in place of the particular apparatus and process B which is schematically illustrated in the drawing. So long as the two phase stream is first separated, after which the gas is treated to extract the more volatile hydrocarbons and then the vapors of such extracted liquids are stabilized by contact with the initially separated liquid phase of the main stream, the purpose of the invention will be accomplished. It is, of course, evident that not only the adsorption unit B, but also the separator 11 and the separator-stabilizer A, are subject to variation in details of construction.

The foregoing disclosure and description of the invention is illustrative and explanatory thereof and various changes in the size, shape and materials, as well as in the details of the illustrated construction, may be made within the scope of the appended claims without departing from the spirit of the invention.

What I claim is:

1. The process of recovering hydrocarbon liquid fractions from a main hydrocarbon stream which has a portion of its constituents in the gas phase and the remainder thereof in the liquid phase, said process including, separating the gas from the hydrocarbon liquids in said main stream, thereafter subjecting the separated gas to an adsorption process wherein said gas is directed through an adsorbent bed to extract hydrocarbon liquid fractions which are more volatile than the hydrocarbon liquids which were separated from the main stream, recovering the extracted liquid fractions as a liquid product, flashing vapors from said liquid product and thereafter intimately contacting the flash vapors from the liquid product with said liquids which were initially separated from the main stream by directing said flashed vapors in countercurrent flow to the initially separated liquids whereby the initially separated liquids absorb a portion of said flash vapors to produce a stable liquid product.

2. The process of recovering hydrocarbon liquid fractions from a main hydrocarbon stream which has a portion of its constituents in the gas phase and the remainder thereof in the liquid phase, said process including, separating the gas from the hydrocarbon liquids in said main stream, thereafter subjecting the separated gas to an adsorption process wherein said gas is directed through an adsorbent bed to extract hydrocarbon liquid fractions which are more volatile than the hydrocarbon

liquids which were separated from the main stream, recovering the extracted liquid fractions from the bed as a liquid product, conducting the liquids which were initially separated from the main stream into a closed zone and directing the same downwardly within said zone, and conducting the liquid product which was recovered by the adsorption process into the lower portion of said zone to cause the flashed vapors from the liquid product to flow upwardly in countercurrent flow to the separated liquids, whereby the intimate contact therebetween produces a stable liquid product.

3. The process as set forth in claim 2, together with the additional steps of conducting the stable liquid product from the lower end of the closed zone to storage, and discharging vapors from the upper end of said zone.

4. The process of recovering hydrocarbon liquid fractions from a main hydrocarbon stream having a portion thereof in the gas phase and the remainder thereof in a liquid phase, said process including, conducting the main stream to a separating zone to separate the gas from the liquid in said main stream, directing the separated gas through an adsorption zone, extracting within said zone hydrocarbon liquid fractions which are more volatile than the liquids initially separated from the main stream, recovering from the bed the extracted liquid fractions as a liquid product, conducting the initially separated liquids into a stabilizing zone to stabilize the same, flowing the stabilized liquid in a downward direction within a contacting zone, conducting the recovered liquid product to a flashing and separating zone to separate flash vapors from the liquid product, directing the flashed vapors upwardly within the contacting zone in countercurrent flow to the downwardly flowing stabilized liquids, whereby said liquids intimately contact said vapors to pick up the same, and discharging said liquids having flashed vapors absorbed therein from the contacting zone.

5. The process as set forth in claim 4, together with the additional steps of withdrawing the liquid product from the flashing and separating zone, and mixing said liquid product with the liquids discharged from the contacting zone to produce a stable liquid product.

6. An apparatus for recovering hydrocarbon liquid fractions from a main two phase stream which includes, a separator for separating the gas from the liquids in said main stream, a hydrocarbon recovery adsorption apparatus having means for extracting and recovering hydrocarbon liquid fractions from the gas as a liquid product, means for directing said separated gas through said apparatus to produce a liquid product which is more volatile than the liquids separated in the separator, means for stabilizing the liquids flowing from the separator, means for separating the vapors which are capable of flashing from the liquids of the liquid product produced in the adsorption apparatus, a vessel having a contacting zone, means conducting the stabilized liquids which were separated in the separator and stabilized into the upper portion of the contacting zone of said vessel, whereby said liquids flow downwardly therein, means conducting the flash vapors which were separated from the liquid product into the lower portion of the contacting zone of the vessel whereby said flash vapors flow upwardly and are intimately contacted by the downwardly flowing liquids to produce a stable liquid product, and means for conducting said stable liquid product from said vessel.

7. An apparatus as set forth in claim 6, with means for mixing the separated liquid of the liquid product with the stable liquid discharged from said vessel.

8. An apparatus for recovering hydrocarbon liquid fractions from a main two phase stream which includes, a separator for separating the gas from the liquids in said main stream, a hydrocarbon recovery adsorption apparatus having means for extracting and recovering hydrocarbon liquid fractions from the gas as a liquid product, means for directing said separated gas through said apparatus to produce a liquid product which is more

volatile than the liquids separated in the separator, a vessel having an upper stabilizing and separating zone, a contacting zone and a lower flashing and separating zone, means conducting the liquids which were separated in the separator into the upper stabilizing and separating zone to flash vapors and thereby stabilize the liquids, said stabilized liquids flowing downwardly through the contacting zone of the vessel, means conducting the liquid product which was produced by the adsorption apparatus into the lower flashing and separating zone to flash vapors from the liquid product, said flash vapors flowing upwardly within the contact zone of the vessel in countercurrent flow to the downwardly flowing liquids to intimately contact said vapors with said liquids to recover a portion of the flash vapors by means of the liquids,

7
said liquids passing downwardly into the lower flashing and separating zone within the vessel to admix with the liquids of said liquid product, and discharging the admixed liquids from the vessel.
